CLAIM

(22) Filed: **Aug. 21, 2000**

The ornamental design for an air flow senser for motorcar, as shown.

(30) Foreign Application Priority Data

DESCRIPTION

Feb. 22, 2000 (JP) 12-007465

FIG. 1 is a front, top and left side elevational perspective view of a air flow senser for motorcar showing our new design;

(51) LOC (7) Cl. **10-04**

FIG. 2 is a front elevational view thereof;

(52) U.S. Cl. **D10/96; D10/50**

FIG. 3 is a right side elevational view thereof;

(58) Field of Search D10/49, 50, 96; 73/118.2, 202, 204.18, 204.25, 204.11, 202.5; 123/494; 701/103

FIG. 4 is a top plan view thereof;

(56) References Cited

FIG. 5 is a bottom plan view thereof;

FIG. 6 is a rear elevational view thereof; and,

FIG. 7 is a left side elevational view thereof.
